UNITED STATES PATENT OFFICE.

WILLIAM J. DOW, OF WASHINGTON, DISTRICT OF COLUMBIA.

VARIABLE CONDENSER.

Application filed March 25, 1925. Serial No. 18,127.

This invention relates to electrical condensers and in particular to that type of variable condenser wherein two interleaved sets of relatively movable plates are employed.

An object of my invention is to provide a combination of two or more of such condenser units, each of which comprises the usual rotatable set of plates or rotor and an adjustable stator set of plates with a novel arrangement of a concentric shaft control for the various movable elements.

Another object of my invention is to provide in such combination means for simultaneously adjusting the rotor elements and selectively adjusting any one of the stator elements but it is contemplated that the combination may be modified to provide means for simultaneously adjusting the stator elements and selectively adjusting the rotor elements.

Another object of this invention is to provide a combination of condenser units which will be compact in form, capable of being used in connection with a great variety of circuits, simple in construction and operation, and economical to manufacture.

Other objects will appear from the detailed description of this invention.

Apparatus of this character is particularly adapted for use in radio receiving circuits wherein several stages of amplification are employed.

Heretofore it has been the common practice to employ a variable condenser in each stage of amplification to properly tune the various circuits to the wave length of the signal received, and adjust each condenser by trial settings until all of the circuits are tuned to give the desired signal strength. If it is desired to receive signals transmitted on a different wave length, the task of resetting the various condensers one by one becomes tedious and involves too great a time element, especially where several stages of amplification are employed.

By employing my novel condenser combination, all of the condenser units may be given simultaneously an approximate initial setting and any one of said condenser units may be further selectively adjusted.

This application is a continuation in part of application Serial No. 709,804 of William J. Dow, filed April 29, 1924.

In the drawings—

Figure 1 is a front view of three condenser units assembled according to my invention in rear of a panel;

Fig. 2 is a similar view with the panel removed;

Fig. 3 is a rear view;

Fig. 4 is a detailed plan view of a concentric shaft control taken on line 4—4 of Fig. 1;

Fig. 5 is a detailed view of the selective cam stator control of Fig. 1;

Fig. 6 is an isometric view showing a modified arrangement of staggered condenser units wherein the stators are simultaneously adjustable;

Fig. 7 is a detailed plan view of a modified concentric shaft control employing a central shaft for a simultaneous stator control and sleeve and cam assembly for selective rotor control;

Fig. 8 shows a selective cam rotor control adapted for use with the modification of Fig. 6;

Figs. 9 and 10 show modified selective controls;

Fig. 11 is a modification of Fig. 1 showing a selective control for central and outer stator elements;

Fig. 12 is a modification showing a remote concentric control for the stator elements;

Fig. 13 is a modification showing a remote control for rotor and stator elements;

Fig. 14 is a modification of Fig. 11;

Fig. 15 is a further modification of Fig. 11;

Fig. 16 is a modification showing a series of condensers aligned axially.

Referring in detail to the drawings, numeral 1 indicates sets of rotor plates and 2 indicates sets of stator plates of condensers. The rotor sets are mounted to rotate with shafts 3 respectively while the stator sets are mounted so as to be adjustable on said shafts. While I have shown three condenser units partially supported on panel 4, two or more units may be used. A bar 5 is provided on the rear end of each shaft 3, the corresponding ends of these bars being pivotally connected to link bars 6 whereby when central shaft 3 is rotated by dial knob 7, a corresponding rotation is given simultaneously to each end shaft.

Surrounding any one of shafts 3, preferably the central one, and rotatable thereon, are provided a series of concentric sleeve like shafts 8, 9 each having a lever 10 and a cam 11 rigidly mounted thereon. A link 12 is rigidly connected to each movable stator element and at its free end loosely engages a corresponding cam 11 whereby when any cam is rotated by the corresponding lever 10, 10 said cam lifts the free end of the engaged link and the stator element connected thereto is rotated. Links 12 may engage cams 11 by their weight alone or may be urged into contact by a spring or equivalent means, or 15 said links may terminate at their ends by a yoke adapted to engage said cams on opposite sides. It is obvious that the range of adjustment of each stator may be determined by the shape of the cam and the point 20 of connection of lever 12.

Fig. 6 shows a modification wherein the stator elements 14 are simultaneously rotatable around rotor shafts 16 and are connected to rotate in unison by links 17. A sleeve shaft 18 is connected to any one of stators 14, preferably the central one, and may be rotated by any appropriate means such as a dial knob as shown. Cams 19 are shown in a conventional form, said cams being carried integrally by sleeve shafts concentric with shaft 18 in a manner shown in Fig. 4 or 7. Each rotor 15 is mounted on a shaft 16 and outer shafts 16 are connected by lateral extensions 21 to links 20 which 35 contact with cams 19. It is to be understood that rotors 15 are so freely mounted that, when cams 19 are lowered by rotation, the weight of links 20 is sufficient to rotate rotors 15. This same feature of operation is employed in Fig. 2 wherein links 12 selectively control stators 2.

In Fig. 6, the central rotor shaft 16 is extended through the center of shaft 18 and cams 19 and may be rotated selectively by any suitable means as shown in Fig. 11.

It is obvious that the bars 5 and links 6 in Figs. 1 to 3 might be replaced by well known equivalents such as a gear, belt or sprocket drive to obtain a simultaneous control of the rotor elements, or in Fig. 6 of the stator elements.

While Figs. 1 to 7 show a cam control means for selective movement of any rotor or stator connected thereto, any equivalent control may be employed such as the pin and slot means in Fig. 9 or the pinion and rack means in Fig. 10.

Fig. 5 shows in detail a selective cam stator control, while Fig. 8 shows a selective cam rotor control.

While in Fig. 1 I have shown a dial knob control on central shaft 3, this control could be placed on any other rotor shaft of the series and the same simultaneous operation 65 would be obtained.

In Fig. 11, I have shown conventionally a central simultaneous control *a* for a series of rotors A, and concentric shaft control means *b*, *c*, *d*, for selective control of a series of stators B, C, D.

In Fig. 12, I have shown conventionally a control *a* mounted on one of the outer rotor shafts and connected to the remaining rotor shafts to move the three rotor shafts in unison. Selective controls for the three 75 stators may be arranged remote from the units as at *b*, *c*, *d* connected respectively to stators B, C, D.

In Fig. 13, I have shown concentric control shafts *a*, *b*, *c*, *d*, all arranged remote 80 from the condenser units, central shaft *a* being connected to each rotor A for simultaneous operation thereof and shafts *b*, *c*, *d*, connected respectively to stators B, C, D, for selective operation thereof. 85

Fig. 14 shows a modification of Fig. 11 wherein the concentric control shafts extend axially through the central condenser unit, the cam and link controls being located in rear of the condensers.

Fig. 15 shows a modification wherein the invention is adapted to a plurality of rotor elements E, E'. The stators G are fixed in position but the outer condenser units comprise relatively movable rotor elements E, E', corresponding rotor elements E in all units being simultaneously adjustable by control *e* and elements E' selectively adjusted by controls *e'*.

Fig. 16 is a modification showing how my invention may be applied to a series of axially aligned condenser units, the stators A, A being simultaneously movable by central control *a* and gears or the equivalents *g*, *h*, *i*. The rotors B, C, D, are selectively adjustable by concentric sleeve shafts *b*, *c*, *d*.

In the operation of the device, each condenser unit is connected with its related circuit which may be a stage of radio frequency. In tuning the receiving set to respond to the frequency or wave length of a particular signal, the rotor elements in Fig. 1 are given an approximate initial setting by rotating dial knob 7 and an accurate setting or balance is completed by moving either of the outer stators with levers 10. In Fig. 6, in addition to reversing the stator and rotor control so as to afford a simultaneous stator control, means are shown to selectively control any one of the three rotor elements, such selective control of each condenser being desirable in certain circuits.

It will be obvious that in Figs. 11 to 13 simultaneous control of rotors is obtained from control *a* while selective control of stators is secured by manipulating various concentric shaft controls *b*, *c*, *d*. 120

What I claim is:

1. In a condenser combination, a plurality 125 of condenser units each unit having selective

ly movable plates, means for simultaneously moving corresponding plates in all of said units, and means for selectively moving other plates of the various units each of 5 said means comprising a control element, said control elements being positioned closely adjacent each other to provide a unicontrol.

2. In a condenser combination, a plurality 10 of condenser units, each unit having selectively movable plates, a plurality of concentric shafts comprising a single set, and means operatively associated with one of said shafts for simultaneously moving corresponding plates of all of said units and means associated with others of said shafts for selectively moving other plates of any 15 one unit.

3. A unitary variable condenser comprising 20 a plurality of variable condensers, means for simultaneously varying the capacities of the condensers, and means including a single set of concentrically arranged control shafts for selectively varying the capacity of each 25 condenser comprising the unit, all of said means being operable from a common point to provide a unicontrol.

4. In a condenser combination, a plurality 30 of condenser units, a single set of concentric control shafts, means associated with one of said shafts for simultaneously varying the capacities of all of said condensers, and means associated with the other shafts for selectively varying the capacities of said 35 condensers.

5. A unitary condenser comprising, in combination, a plurality of variable condenser units, each unit having a series of main movable plates and an auxiliary movable plate, means for simultaneously moving said main movable plates, a plurality 40 of concentric shafts, and means associated with each concentric shaft for moving a desired auxiliary movable plate, all of said 45 means being operable from a common point to provide a unicontrol.

6. In a condenser combination, a plurality 50 of condenser units, each unit having selectively 55 movable plates, a plurality of concentric shafts, one of said shafts being connected to corresponding movable plates in all of said units, and each of said other shafts being connected respectively to other movable plates in the various units.

7. In a condenser combination, a series 60 of aligned condenser units, each unit having selectively movable plates, a control shaft operatively connected to corresponding plates of each unit for simultaneous control thereof, a plurality of tubular shafts concentric with said control shaft, and means associated with said tubular shafts for selectively moving other plates of each unit.

8. A condenser combination comprising a plurality of variable condenser units, shaft 65 supporting means for the rotatable elements of each condenser unit, means for rotating said means, and means including a single set of concentrically arranged control shafts 70 for selectively adjusting the normally stationary elements.

9. In a condenser combination, a plurality 75 of condensers aligned in a common plane, each condenser having plates selectively movable in said plane, a plurality of concentric shafts, one of said shafts being connected to corresponding movable plates of each condenser for simultaneous rotation thereof, the other of said shafts being connected to the remaining movable plates of 80 said condensers for selective rotation thereof.

10. In a condenser combination, a plurality 85 of condensers aligned in a common plane, each condenser having plates selectively movable in said plane, rotatable shafts for supporting corresponding movable plates in said condensers, means connecting said shafts for simultaneous rotation thereof, a plurality of tubular shafts surrounding one 90 of said first mentioned shafts, and means connecting said tubular shafts to other movable plates in said condensers for selective rotation thereof.

In testimony whereof I affix my signature.
WILLIAM J. DOW.
